UNITED STATES PATENT OFFICE.

CARL F. GERLINGER, OF DALLAS, OREGON.

RAILWAY-BRAKE.

No. 895,851.

Specification of Letters Patent.

Patented Aug. 11, 1908.

Application filed April 22, 1908. Serial No. 428,643.

To all whom it may concern:

Be it known that I, CARL F. GERLINGER, a citizen of the United States, residing in Dallas, in the county of Polk and State of Oregon, have invented certain new and useful Improvements in Railway-Brakes, of which the following is a specification.

My invention relates to that class of railway brakes in which, when a car-wheel is derailed, brakes are automatically applied to stop the car or the train.

The object of my invention is to provide simple and reliable mechanism of this class and in carrying out my invention I provide a cross-bar extending transversely across the truck parallel with an adjacent axle and which extends over the rails of the track. This bar is supported on brackets or bars attached to opposite journal-boxes and it supports a valve-casing connected in any suitable way with the train-pipe of the brake system. From the cross-bar above mentioned is suspended another cross-bar of the same dimensions which is connected with the first-mentioned cross-bar by vertical bolts carrying springs which normally press the lower movable cross-bar away from the upper stationary one. The arrangement is such that when a wheel is derailed the adjacent end of the lower movable cross-bar strikes the rail from which the wheel was derailed and causes a valve to operate to open the train-pipe and permit an exhaust which will operate the brakes.

In the accompanying drawings illustrating my invention, Figure 1 is an end elevation of so much of a car-truck with my improvements applied as is necessary to illustrate my invention, the parts being in their normal condition. Fig. 2 is a similar view in the derailed position. Fig. 3 is a perspective view showing more particularly the construction of the frame-work of the truck adapting it to support my improved brake-operating-devices. Figs. 4 and 5 show details. The car-truck proper may be constructed in any suitable way, the frame-work A being of usual construction attached to the journal-boxes B in the usual way. From the journal-boxes extend the upper and lower frame-bars C, C', which are rigidly connected with a cross-bar D. This cross-bar extends across the truck parallel with the axle D' but below the horizontal plane thereof. It supports a valve-casing E, connected by a tube F with the train-pipe of the brake system.

e indicates the valve-seat and G indicates the vertically operating valve which is preferably provided with guides g.

f indicates an exhaust opening in the valve-casing below the valve-seat.

Below the cross-bar D is another cross-bar H which may be of the same dimensions. It is suspended from the cross-bar D by means of vertically arranged bolts I on which are arranged between the bars D and H springs J. The bar H is normally held in the position shown in Fig. 1 by its own weight and by the power of the springs J. The valve-stem K extends down through an opening in the cross-bar D and approaches close to the upper surface of the cross-bar H. When the parts are in the positions shown in Fig. 1, the truck can move in the usual way without interfering with the brake-mechanism but should a wheel become derailed the cross-bar H will abut against the adjacent rail in the manner indicated in Fig. 2 and the cross-bar H will be moved towards the bar D, striking the valve-stem K and opening the valve. This will exhaust the train-pipe and cause the brakes to be applied.

As brake-mechanism of this class is often equipped with signals, it is obvious that when my improved mechanism operates in the manner above mentioned, signals may be applied at various parts of the train. As many sets of the mechanism described as are found necessary in use may be applied to the various trucks.

The devices are simple in construction, easily made and easily applied without material alteration in the general construction of the truck or the brake mechanism.

I claim as my invention:

1. The combination with a truck-frame of a cross-bar rigidly connected with the frame, a cross-bar suspended from said first-mentioned cross-bar and valve-mechanism connected with the train-pipe of the brake-mechanism which is operated by said suspended cross-bar.

2. The combination with the journal-boxes of brackets secured thereto, a cross-bar rigidly secured to said brackets, another cross-bar of the same length, yieldingly supported from said first-mentioned cross-bar, and valve-mechanism supported by the first-mentioned bar connected with the brake system and operated by the suspended cross-bar.

3. The combination with the journal-boxes of a truck, of a cross-bar rigidly supported thereby, a valve-casing mounted on said cross-bar and connected with the train-
5 pipe of a brake system, a valve operating in said casing and having a stem extending through the cross-bar, another cross-bar suspended from the first-mentioned cross-bar,

and springs interposed between said cross-bars for the purpose specified.

In testimony whereof, I have hereunto
subscribed my name.

CARL F. GERLINGER.
